DAVID GOLDICH, OF WINSTED, CONNECTICUT.

ELECTRIC-FIXTURE FITTING AND METHOD OF MAKING SAME.

1,407,527.

Specification of Letters Patent. Patented Feb. 21, 1922.

Application filed August 27, 1920. Serial No. 406,469.

To all whom it may concern:

Be it known that I, DAVID GOLDICH, a citizen of the United States, and a resident of Winsted, in the county of Litchfield and State of Connecticut, have invented a new and Improved Electric-Fixture Fitting and Method of Making Same, of which the following is a full, clear, and exact description.

10 This invention relates to a fitting for electric fixtures and the method of making the same, and has reference particularly to a new and improved form of "hickey" and to its method of manufacture.

15 An object of the invention is the provision of a method by which the fitting is simply and efficiently formed from a single piece of sheet metal in a minimum number of operations, whereby a great saving of time and 20 labor is achieved, with a resultant product which is much superior in finish to devices of this type already known.

Another object resides in the provision 25 of a new and improved form of hickey which, in its completed state, presents a finished appearance, whereby smooth edges and surfaces are presented in the use of the device to insulated electric circuit wires so that the insulation is not worn out by contact 30 with rough surfaces on the fitting.

A further object is to provide a fitting which can be constructed in large quantities, by stamping sheet metal, at a minimum cost.

35 A still further object resides in the provision of a fitting which has greatly increased strength, owing to the elimination of flaws which are resident in cast fittings.

Another object resides in the provision of 40 the particular sequence of operation forming the above-mentioned method and the construction of the fitting, which will be hereinafter set forth in the description and claims and shown in the accompanying drawings.

45 Heretofore in manufacturing electric fittings such as hickies, which are used in connection with conduits containing electrical circuit wires whereby the various wires may be readily and simply led out to their respective connections, these fittings have been cast. This casting has resulted, generally, in the presentation of rough, irregular surfaces which when coming in contact with the insulation on the wire has caused the tearing 50 of the same, resulting in short circuit. Furthermore, by reason of being cast, previously

made hickies have contained within their structure flaws which made them liable to be broken during use. The casting process is, moreover, slow compared to the process 60 conceived in accordance with my invention, which contemplates stamping the hickey, by a series of consecutive steps, from sheet metal in one piece, whereby added strength is given to the fitting in that it has no inherent flaws and in which smooth surfaces and edges are present in the final product, so that no finishing is required of the manufacturer after the stamping is completed. 65

My operation, in general, comprises passing 70 a sheet of stamped metal through a press and piercing at intervals therein a plurality of spaced apertures, after which another tool is brought into action upon the sheet metal in connection with these apertures to 75 simultaneously draw flanges on certain of the apertures at the same time that a blank including the apertures is cut out of the sheet metal. This blank is then passed to a bending machine in which the blank is bent 80 so as to align the flanged apertures with a common axis, and have a plurality of integral arms connecting these flanged portions.

The invention is illustrated in the drawings, of which—

85 Figure 1 represents a central vertical section taken through an electrical fixture or conduit showing my improved fitting or hickey in place;

Figure 2 represents a strip of sheet metal 90 from which the fitting is stamped by a succession of operations;

Figure 3 is an end view of the fitting; and Figure 4 is a side view of the fitting.

As shown in the drawings, 1 represents 95 an electrical fixture or box of any suitable nature into which electrical conduits 2 are adapted to extend. These conduits are adapted to carry insulated wires, such as 3, which pass therethrough in any relative 100 direction. The fitting or hickey which is the embodiment of my invention is shown and represented by the numeral 4. This fitting or hickey comprises a pair of plates 5 and 6, each of which is provided with an 105 integral, turned-up, flanged collar portion 7. A pair of connecting arms 8 and 9 extend between the plates 5 and 6 and are integral with the metal thereof. These arms extend in a line at right angles to the planes of plates 5 and 110 6 which are disposed parallel to each other with the apertures or collars 7 in line with

a common axis. As shown in Figure 1, the arms 8 and 9 are adapted to support certain of the wires 3 when these wires are bent or turned to pass from one conduit 2 into another. Each of the collars 7 is internally threaded, as designated by the numeral 10, and is adapted to engage with a similarly threaded portion on the conduit to which it may be connected. Opposite edges of the plates 5 and 6, as shown in Figure 3, are formed in straight lines parallel to each other, such as 11 and 12, so that either end of the fitting or hickey may be manipulated by a wrench to be readily attached to or removed from a conduit.

This fitting is made from one single piece of sheet metal of any desired strength or quality. Its formation is roughly indicated in Figure 2. In this figure, 13 represents a strip of sheet metal of the desired size, strength and quality. This strip is passed through a stamping press of any suitable type, and in its passage therethrough is successively subjected to a series of operations hereinafter set forth. In the first place, a tool in the head of the press is provided to stamp out in one movement the apertures 14 and 15, shown in Figure 2 on the left-hand portion of the strip 13. The strip is then moved to the right, where another and compound tool in the same machine is provided, which is adapted simultaneously to enter the apertures 14 and enlarge them to the diameter designated at 16 in the right-hand side of Figure 2; and by so enlarging these holes it turns up integral with the strip 13 the collars 7 above mentioned. At the same time that this drawing action is taking place, another part of the compound tool cuts out a blank 17, which includes the apertures 15 and 16.

This blank 17 is then passed to another machine in which the plates 5 and 6, with the collars 7 thereon, are bent parallel to

each other and at right angles to the connecting arms 8 and 9. By this process it is seen that I am enabled to manufacture in a substantially shorter time a much larger number of fittings or hickeys than can be produced by the old fashioned casting method. Moreover, this fitting, by being stamped from one piece of metal, is inherently stronger and less likely to contain flaws than the cast product. Further, it presents to the insulation of the wires with which it comes in contact a much smoother, more regular surface, so that the insulation is not injured, causing short circuits.

I claim:

1. An electrical fitting of stamped sheet metal comprising a pair of spaced parallel plates, a plurality of integral arms connected with said plates, and a collar formed on each plate, said collar being internally threaded.

2. An electrical fitting of stamped sheet metal comprising a pair of parallel plates, and a plurality of integral arms connected with said plates, each of said plates being provided with an internally threaded hole.

3. An electrical fitting of stamped sheet metal comprising a pair of spaced parallel plates, an integral internally threaded flanged collar on each of said plates, said collars being aligned parallel to each other and with respect to a common axis, and integral, spaced connecting arms between said plates.

4. An electrical hickey of stamped sheet metal comprising a pair of plates spaced apart and provided with suitable apertures, an integral flanged collar on each plate surrounding the apertures, and integral, spaced connecting arms between said plates, said plates, said collars and said connecting arms being formed from one piece of metal.

DAVID GOLDICHI.
